UNITED STATES PATENT OFFICE.

GEORGE E. SWAN, OF BEAVER DAM, WISCONSIN.

CURTAIN-FIXTURE.

SPECIFICATION forming part of Letters Patent No. 296,299, dated April 1, 1884.

Application filed January 23, 1884. (No model.)

To all whom it may concern:

Be it known that I, GEORGE E. SWAN, a citizen of the United States, residing at Beaver Dam, in the county of Dodge and State of Wisconsin, have invented certain new and useful Improvements in Curtain-Fixtures; and I do hereby declare the following to be a full, clear, and exact description of the invention, such as will enable others skilled in the art to which it appertains to make and use the same.

This invention relates to that class of curtain-fixtures which are designed to secure the weight-stick to the bottom of the curtain; and its object is to provide simple, durable, inexpensive, and efficient means whereby the stick may be detachably secured to the curtain without sewing or stitching.

To this end my invention consists, substantially, in simply folding the end of the curtain around the stick and then securing it thereto by a series of adjustable and removable spring-clamps, which are pressed on so as to tightly embrace and bind against the stick and securely retain the curtain to the latter.

In the drawings, Figure 1 is an elevation of the lower or end portion of a window-curtain having my invention applied thereto. Fig. 2 is a transverse detail sectional view of the same. Fig. 3 is a detail perspective view of one of the clasps. Fig. 4 is a detail perspective view illustrating a modification of the formation of the clasps.

Corresponding parts in all the figures are denoted by the same letters of reference.

Referring to the drawings, A designates the weight-stick, which may be of any suitable construction, but is preferably of the usual flat form, as herein shown.

B is the curtain, which has its end portion, 40 b, folded around the stick, as shown, its edge b' being brought down within the fold to obviate fraying or other damage. If desired, this end portion, b, may be folded a number of times around the stick, but the single fold herein shown is sufficient to secure an effective result.

C designates the clasps, which are of approximately U shape, and preferably conform to the contour of the stick. These clasps are disposed in a longitudinal series along the stick, 50 and are simply pressed up into position, so that their spring side portions, c c, tightly clasp all parts of the fold of the curtain to the stick, and

thus the stick and curtain are secured together without sewing, stitching, or the like.

It is obvious that my improved means of attachment permit of a ready and convenient separation of the curtain and stick, when desired, for purposes of substitution or laundering, by simply slipping the clasps off, and the parts are as readily connected again by 60 slipping or pressing the clasps in position.

The clasps are preferably formed of sheet-steel, bent into the requisite form, and having its side portions, c c, convexed, as shown, to secure the desired power of spring tension 65 and to enable the clasp to adapt itself neatly to the stick. The ends c'c' of the spring sides c c are bent or curved outwardly to facilitate the adjustment of the clasp to the stick. The smooth inner surfaces of these ends will not 70 tear or injure the curtain fabric as the clasp is being slipped on and off, and these slightly-outturned ends obviate any engagement of the said ends with the fabric.

In the modification shown in Fig. 4 the clasp 75 is of corresponding contour, but is formed of spring-wire, and it is provided with an extension, c', adapted to serve as a handle by which the curtain may be operated. The central clasp of the series may be provided with a ring 80 or handle for this purpose.

I do not wish to be understood as limiting myself to the exact construction and arrangement herein shown and specified, as numerous modifications may be made without departing 85 from the spirit and scope of my invention.

The operation and advantages of my invention will be readily understood from the foregoing description and annexed drawings. It is neat and ornamental, and obviates all labor 90 and trouble consequent upon sewing the stick in the curtain. It can be very readily and conveniently applied, and is durable and efficient. The spring-tension of the clasps is of sufficient power to enable them to securely encircle or embrace the stick and prevent any accidental displacement of the parts.

I claim as my invention—

1. As an improvement in securing curtains to their weight-sticks, the combination, with 100 the weight-stick and the curtain fabric having its end folded around the same and unsecured thereto, of a series of spring-clasps binding this folded end securely to the stick, said clasps

being adapted to be removed when it is desired to disconnect the curtain from the stick, substantially as set forth.

2. The combination of the weight-stick, the curtain fabric folded around the same, with its edge within the fold, as set forth, and unsecured to the stick, and the approximately **U**-shaped securing-clasps formed with convex side portions, and having the outwardly-curved top ends, whereby the fabric is bound to the stick, substantially as set forth.

3. The combination of the weight-stick, the curtain fabric having its end folded around the stick to retain the same, and unsecured to the stick, and approximately **U**-shaped securing-clasps binding the folded end permanently to the stick and against any movement or disen-

gagement, the stick and curtain being disconnected when the clasps are removed, substantially as and for the purpose set forth.

20

4. As an improved article of manufacture, the herein-described clasp for weight-sticks, bent up into approximately **U** shape, with convexed spring side portions, and having its ends curved outwardly, whereby the clasp may be pressed onto the stick or disengaged therefrom without engaging or injuring the curtain fabric, substantially as set forth.

25 In testimony whereof I affix my signature in presence of two witnesses.

GEORGE E. SWAN.

Witnesses:

E. ELWELL,
JAS. WELCH.
